UNITED STATES PATENT OFFICE.

TOM WATKINS, OF GATEWAY, COLORADO.

REIN SUPPORT.

Application filed August 3, 1926. Serial No. 126,868.

This invention relates to rein supports and particularly to certain improvements in the rein support shown, described and claimed in my application for patent filed September 10, 1924, Serial No. 737,011, and allowed on the 7th day of June, 1926.

The general object of the present invention is to provide a rein support which is adapted to be attached to a wagon tongue 10 to provide means for preventing the reins from catching beneath the tongue.

Another object is to provide a device of this character which will yield when forcibly brought into contact with an obstruction and 15 in which its general position will change in the event that the device is brought into contact with a rigid obstruction such as a fence, the side of a barn, or the like.

A further object of the present invention 20 is to provide means whereby the outer coils of the resilient rein support may be rotatably connected to the helically coiled portion of the support, the construction being such that the rein engaging portion will not 25 readily become detached from the helically coiled portion.

A further object is to provide improved means whereby the rein support may be connected to the tongue of the wagon.

Other objects will appear in the course 30 of the following description.

My invention is illustrated in the accompanying drawings wherein:—

Figure 1 is an elevation of a rein support constructed in accordance with my invention;

Fig. 2 is a section on the line 2—2 of Figure 1;

Fig. 3 is a section on the line 3—3 of 40 Figure 2;

Fig. 4 is a section on the line 4—4 of Figure 1;

Fig. 5 is a fragmentary perspective view 45 of the inner end of the spring member 11;

Fig. 6 is an elevation of the plate with which the coils of the spring 10 are engaged.

Referring to these drawings it will be seen that I have illustrated the cap end of a

wagon tongue T having secured thereto the usual clevis C. My improved device comprises a clamp adapted to be secured to the clevis, a relatively resilient portion 10 composed of a coiled spring or springs, and the rein supporting portion 11. The particular construction of the portions 10 and 11 will be later stated.

The clamp whereby the portion 10 is clamped to the forward end of a wagon tongue and specifically to the clevis C is composed of a plate 12 having an angularly extending flange 13 at its rear end. This flange is cut away at 14. This plate 12 is formed with a depression or channel 12^a to receive the inner end portion of the wire coil 26 which forms the portion 10, which will be later described. Coacting with this plate 12 is a U-shaped clamping member 15 having parallel portions or ears 16 apertured for the passage 65 of a stud bolt 17 which, at its rear end, is integrally connected to a semi-circular clamping member 18 which is adapted to embrace or partially encircle the portion 10.

Riveted to the rear wall 19 of the member 75 15 is a spring 20 and formed to provide two approximately semi-circular spring leaves normally spaced from each other at 21. The bolt 17 passes through the apertures in the plate 12 and the side plate 16 and surrounding this bolt is a coiled spring 22 against 80 which the nut 23 bears. The plate 12 has inwardly turned margins 24 adapted to clamp over the rounded edges of the clevis C and preferably a piece of leather, raw 85 hide, or like material designated 25 will be disposed on the inner side of this plate 12.

The spring 20 will bear resiliently against the inner face of the clevis C and will expand to suit different sizes of clevises, while the plates 12 and 16 will bind on each side of the clevis. Thus the clevis will be securely clamped and the portion 10 will also be securely clamped to the clamping members 12 and 16.

The portion 10 is constructed in accordance with my prior application, of two coils of wire 26 and 27 disposed one within

the other. The inner extremities of these two wires, from which these two coils are formed, are extended through an end plate 28 which is approximately semi-circular in 5 form and provided with two slots or perforations 29 through which the two wires 26 and 27 extend. The ends of these wires are flattened down upon this plate and the straight edge of this plate normally rests 10 within the slot 14 and against the edge wall of this slot so that the plate cannot turn. The outer end of the tubular member 10 is preferably bulged as at 30. The portion 11 is formed of two wires 31 and 32, these wires 15 being coiled as illustrated in Figure 5 so as to form a series of parallel coils and these two series of overlapping coiled wires are connected to each other at intervals by binding rings or wires 33. The inner ends of the 20 wires 31 and 32 are bent upon themselves as at 34 and each of these rebent portions 34 is so formed that the rebent wire is turned outward at 35 to fit the bulged portion 30 in the coils of the wires 26 and 27. Thus 25 these portions 34 of the two wires 31 and 32 may be inserted within the tubular coils 26 and 27 and sprung into place within the bulge 30 so that this outer portion 11 has in effect, swiveled engagement with the portion 10, thus permitting this part 11 to be rotated within the part 10.

The part 11, as illustrated in Figure 1, is upwardly curved so as to form a slight hook upon which the reins may be supported. 30 Thus, the reins when dropped are prevented from passing below the tongue T and thus will save the driver from climbing down from the wagon to rearrange the lines. This is particularly convenient where the 35 tongue is attached to a hay wagon or the like where the driver is perched up some distance from the tongue. The structure of the rein support is such that it is normally maintained in a fixed position but in the 40 event that the supporting member should strike a fence, side of a barn, or any other obstruction, the supporting member will yield sufficiently as to prevent breakage but will, because of its resiliency, automatically 45 return to its normal position and condition. This supporting device will also yield sufficiently as to offer no obstruction to the teamster when hooking up or unhooking. By providing a swiveled connection between 50 the portions 10 and 11 the two sections or portions will not ordinarily pull apart but yet the teamster is enabled to twist the outer section 11 as he pleases to the right or left. This reduces the cost of manufacture and 55 very greatly improves the rein support as illustrated in my prior application.

The particular construction of the clamp whereby the rein support is attached to the tongue is such that it may be applied to 60 clevises or pole caps of different sizes as the

spring 20 readily accommodates itself to eyes of different diameters.

I claim:

1. A rein support comprising an elongated yieldable member formed of two sections 70 or portions having swiveled engagement with each other, and means for connecting the member to a wagon tongue.

2. A rein support comprising an elongated yieldable resilient member formed of two 75 sections, the sections being swivelly connected to each other, the inner section having a tongue engaging clamp and the outer section being formed to provide an upturned resilient hook.

3. A rein support formed of two sections, one of said sections consisting of an outer and an inner helically coiled wire, the inner end of said section carrying a tongue engaging clamp, the outer end of the coiled 85 wire being outwardly bulged, and a hook-shaped resilient outer section composed of a plurality of wires, the inner end of each of said wires being bent upon itself to form a bight portion, the sides of which are laterally upturned to fit the bulge in the coils of the first named section.

4. A rein support comprising a yieldable member, the outer end of which is hook-shaped, a clamp bolt having a portion partially embracing the inner end of said yieldable member, opposed clamping plates through which said bolt passes, a spring surrounding the bolt and yieldingly resisting inward movement of the clamping plates, and a spring attached to one of said clamping plates, the spring having the form of a segment of a circle to provide two leaves resiliently urged away from each other, said spring being adapted to be disposed within 100 the eye of a tongue clevis, while the bolt passes through said eye.

5. A rein support including a tubular resilient member, and means for clamping the rein support upon the clevis of a wagon tongue comprising a bolt having a flattened portion at its inner end adapted to partially embrace the tubular member section, a U-shaped member embodying opposed parallel plates perforated for the passage of the bolt, 110 a plate disposed between said tubular member and one of the side plates of said member, said plate being angular in section and having an aperture for the passage of the bolt, a circular split spring disposed between the 115 sides of said U-shaped member and adapted to expansively engage the interior of the clevis eye, a nut engaging the bolt, and a coiled spring surrounding the bolt and resisting compression of the sides of the U-shaped member.

6. In combination with a wagon tongue, a plate carried thereby and provided with a groove, a rein support having a circular shank engaged in said groove, a bolt ex- 125

tended through the plate and having a hooked end engaging said shank, a nut on said bolt at the opposite side of the plate from the shank, and a spring extending 5 from the plate and engaging said nut.

7. In combination with a wagon tongue, a plate carried thereby and provided with a groove, a rein support having a circular

shank engaged in said groove, a bolt extended through the plate and having a hooked end engaging said shank, and means constantly urging said hook toward said plate. 10

In testimony whereof I hereunto affix my signature.

TOM WATKINS.
